UNITED STATES PATENT OFFICE

95,127

DESIGN FOR AN ENGINE HOOD FOR MOTOR VEHICLES

Maximilian C. Frins, Plainfield, N. J., assignor to
International Motor Company, New York,
N. Y., a corporation of Delaware

Application November 9, 1934, Serial No. 53,957

Term of patent 14 years

To all whom it may concern:

Be it known that I, Maximilian C. Frins, a citizen of the United States, residing in the city of Plainfield, in the State of New Jersey, have invented a new, original, and ornamental Design for an Engine Hood for Motor Vehicles, of which the following is a specification, reference being had to the accompanying drawing, forming a part thereof, in which:

Figure 1 is a view in front elevation of an engine hood for motor vehicles which shows the design, and

Figure 2 is a side view thereof.

I claim:

The ornamental design for an engine hood for a motor vehicle, as shown.

MAXIMILIAN C. FRINS.
